W. S. MORGAN

MEANS FOR GRINDING DREDGE BUCKETS AND THE LIKE

Filed Aug. 3, 1922

By *Jaet. Richmond*

Attorney

UNITED STATES PATENT OFFICE.

WALTER S. MORGAN, OF HIGH BRIDGE, NEW JERSEY, ASSIGNOR TO TAYLOR-WHAR-
TON IRON AND STEEL COMPANY, OF HIGH BRIDGE, NEW JERSEY, A CORPORA-
TION OF NEW JERSEY.

MEANS FOR GRINDING DREDGE BUCKETS AND THE LIKE.

Application filed August 8, 1922. Serial No. 579,404.

To all whom it may concern:

Be it known that I, WALTER S. MORGAN, a citizen of the United States, residing at High Bridge, in the county of Hunterdon 5 and State of New Jersey, have invented certain new and useful Improvements in Means for Grinding Dredge Buckets and the like, of which the following is a specification.

10 This invention provides a method and means for the rapid and economical grinding of dredge buckets and the like. Dredge buckets are ponderous constructions, usually of unmachinable steel, and have heretofore offered serious difficulties in grinding; their shape and weight, up to two tons, necessitating that they be ground one at a time. My invention makes it possible to grind them in multiples of two or more.

15 The nature, characteristic features and scope of the invention will more readily be understood from the following description taken in connection with the accompanying drawing, wherein,—

20 Figure 1 is a perspective view of apparatus for carrying out the method.
Fig. 2 is a front elevational view.
Fig. 3 is a top view; and
Fig. 4 is an end view.

25 According to my invention I center the buckets so that they straddle one another or interlock, with similar eyes in coincidence and two of them overlapping. In the illustrated embodiment of the invention, use 5 is made of a pair of rotatable face plates connected by adjustable spacing and work support plates 6. The face plates are peripherally supported on flanged rollers 7 arranged in pairs and driven by suitable

means (not shown) in order to impart rotary movement to the face plates.

The buckets 8 are supported on the plates 6, so that their eyes 9 are in registry and two of them overlapping, and they are secured in such relation by V blocks 10, or other appropriate means adjustable with respect to the work plates 6 to which they are clamped through the medium of T slots or the like. The grinding elements 11 are then brought into play in the usual manner 50 to internally grind the eyes 9, the face plates being bored, as at 12, to permit the passage of the grinding elements. It will be evident to those skilled in the art that by my method of grinding dredge buckets, 55 in multiples of two or more, I not only effect a desirable economy, but obtain uniformity in grinding.

Having described my invention, I claim,—

1. In a means for grinding dredge buckets and the like, a rotatable work holder, 60 means for supporting a plurality of dredge buckets therein with the eyes of one aligned with the eyes of the others and concentric with the axis of the holder, said holder being formed for the passage of lapping tools through such aligned eyes.

2. In an apparatus for grinding dredge buckets in multiples of two or more, a peripherally-supported holder having an 70 axially-disposed opening for the passage of a grinding tool, and means for supporting the dredge buckets to cause their eyes to register in alignment with such axially-disposed opening.

75 In testimony whereof I affix my signature.

WALTER S. MORGAN.
